UNITED STATES PATENT OFFICE.

ALBERT A. GUARDIA, OF CHICAGO, ILLINOIS, ASSIGNOR OF ONE-HALF
TO MELVIN BAKER, OF CHICAGO, ILLINOIS.

COVER ATTACHMENT FOR TABLES OR COUNTERS.

SPECIFICATION forming part of Letters Patent No. 771,009, dated September 27, 1904.

Application filed November 6, 1903. Serial No. 180,117. (No model.)

To all whom it may concern:

Be it known that I, ALBERT A. GUARDIA, a citizen of the United States, residing at Chicago, in the county of Cook and State of Illinois, have invented certain new and useful Improvements in Cover Attachments for Tables or Counters; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to a cover attachment for tables or counters, and has for its object to provide a device by which a display of goods on a table or counter may be conveniently covered.

20 With this object in view the invention consists in certain novel features of construction hereinafter described and claimed, and shown in the accompanying drawings, in which—

Figure 1 is a perspective view showing the 25 cover in use. Fig. 2 shows the cover when not in use. Fig. 3 is a fragmentary view showing the means for securing the free end of the cover.

Referring specifically to the drawings, A indicates a table or counter. At one side thereof, under the projecting edge of the top, are secured brackets D, which support a spring-roller B, carrying a cover C.

At J is indicated the angular stem of the 30 roller by which it is wound.

A guard-plate E extends partially around the roller, so that when the cover is wound thereon it will be protected. The parts are

also concealed thereby, so as not to mar the appearance of the table. The guard-plate is 40 fastened to the table by screws G and is further secured thereto by fingers F, projecting from the brackets D. To the free end of the cover a rod H is secured, which is of such a length as to lie outside of the guard-plate when 45 the cover is wound on the roller, so that it may be readily grasped and unwound for extending it over the goods, as shown in Fig. 1. When the cover is in use, the rod H on the free end thereof is secured by hooks K on the 50 opposite side of the table, by which the cover is held in extended position. The cover is preferably made of some waterproof fabric, so as to effectively protect the goods.

Having thus described my invention, what is 55 claimed as new, and desired to be secured by Letters Patent, is—

1. The combination with a table, of a spring-roller secured at one edge thereof, a cover on the roller extensible over the table and having 60 a rod secured on its outer end, and hooks on the opposite side of the table to receive the rod for holding the cover in extended position.

2. The combination with a table, of a spring-roller secured at one edge thereof, a cover on 65 the roller extensible over the table and having a rod secured on its outer end, hooks on the opposite side of the table to receive the rod for holding the cover in extended position, and a guard-plate over the spring-roller. 70

In testimony whereof I affix my signature in presence of two witnesses.

ALBERT A. GUARDIA.
